UNITED STATES PATENT OFFICE.

ROBERT BEGICH AND GEORGE JAKOPEC, OF CHICAGO, ILLINOIS.

SHAFT AND ELEVATOR CONSTRUCTION FOR HANDLING MATERIAL.

Application filed January 19, 1928. Serial No. 247,990.

This invention relates to certain new and useful improvements in a shaft and elevator construction for handling material.

The primary object of the invention is 5 to provide a shaft and elevator construction for handling material and is intended for various uses as in excavation work or mining for elevating material to a point of discharge.

10 A further object of the invention is to provide of shaft and elevator construction for handling material in which the elevator for raising the material effects operation of a pivotally mounted chute into which the 15 elevator dumps the material for lateral discharge, trap doors in the shaft adjacent the ground line being operatively connected to the chute for shifting movement to closed position when the chute is disposed to receive the charge from the elevator to prevent the material from falling downwardly 20 in the shaft. A still further object of the invention is to provide in apparatus of the above type, a locking device for the elevator 25 when in dumping position, the locking device automatically releasable upon upward movement of the elevator following its dumping operation.

With the above and other objects in view 30 that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view, partly 40 broken away of a shaft and elevator construction for handling material, a stationary engine being fragmentarily illustrated and having a cable connection with the elevator;

Figure 2 is a side elevational view of the 45 shaft construction showing the shiftable discharge chute positioned outwardly of the runway of the shaft and with the elevator adjacent the ground line of the shaft with the trap door for the shaft in open position;

Figure 3 is a side elevational view, similar 50 to Figure 2, showing the discharge chute shifted into the runway of the shaft and the elevator disposed above the chute in dumping position with the trap doors for the shaft closed;

Figure 4 is a fragmentary elevational view of an indicator device associated with the hoisting mechanism for determining the position of the elevator in the shaft;

Figure 5 is a detail sectional view taken 60 on line 5—5 of Figure 4;

Figure 6 is a vertical sectional view taken on line 6—6 of Figure 1 showing the elevator at the upper end of the shaft with one of the parts carried thereby engaged with 65 an operating member for the discharge chute, with the chute shifted outwardly of the runway of the shaft;

Figure 7 is a detail sectional view, similar 70 to Figure 6 showing the elevator supported in the shaft against descending movement and the discharge chute shifted into the runway of the shaft beneath the elevator, the bottom doors of the elevator being illustrated in dotted lines in open position;

Figure 8 is an enlarged detail sectional view taken on line 8—8 of Figure 3 showing the elevator disposed above the discharge chute and locked to the guard rails for the elevator;

Figure 9 is a sectional view similar to 80 Figure 8 showing the bottom doors of the elevator in open position;

Figure 10 is a horizontal sectional view taken on line 10—10 of Figure 8; and

Figure 11 is a horizontal sectional view taken on line 11—11 of Figure 3.

As shown in Figures 1 to 3, the invention would relate to a shaft and elevator construction for the handling of material comprises 90 a shaft structure designated by the reference numeral 1 in which an elevator 2 is vertically movable, the shaft 1 and elevator 2 having cable and pulley devices associated therewith that extend to a stationary engine 95 3 for operating the elevator. The shaft 1 has a discharge chute 4 shiftably mounted thereon, normally assuming a position outwardly of the runway of the shaft and to be shifted into the runway of the shaft to receive the contents of the elevator for lateral discharge thereof as shown in Figure 3, the discharge chute being automatically operated by devices arranged in the path of movement of the elevator while locking devices 100 5 carried by the elevator are engageable with the shaft for holding the elevator against movement during a dumping operation. The details of construction and the complete 105 operation of the shaft and elevator con- 110

struction will be clearly set forth in the following specific description.

The shaft 1 comprises a base plate or ground platform 6 upon which the upper structure of the shaft that comprises the corner post 7 is mounted, the corner post being connected by suitably spaced cross braces 8, the cross braces at the extreme upper end of the shaft supporting a cross beam 9. 10 The opposite sides of the shaft 1 at the ends of the cross beam 9 have guide rails 10 that extend from the upper end of the shaft downwardly below the ground line to the desired depth to act as a guide for the elevator 2.

The elevator 2 comprises a hoist bucket 11 that is open at its upper side with the lower end thereof closed by doors 12 hinged thereto as at 13, the doors being normally retained in closed position by devices to be presently described. The elevator or hoist bucket 11 is carried by an inverted U-shaped frame comprising side bars 14 and a cross head bar 15, the side bars 14 being grooved at their outer sides for sliding engagement with the guide rails 10. As shown more clearly in Figures 8 and 9, the bottom closure doors 12 for the hoist bucket 11 are hinged at their outer edges to opposite side walls of the bucket while the meeting edges of the bottom closure doors at 10 carry outwardly directed pins 16 that have flexible connections 17 that extend upwardly through passages formed in the side bars 14 for attachment as at 18 to the cross bar 19 that is movably mounted at its end in grooves formed in the inner faces of the side bars 14 between the upper end of the hoist bucket 11 and the upper cross bar 15 of the inverted U-shaped frame. When the cross bar 19 is lowered as shown in Figure 9 to occupy a position adjacent the upper end of the hoist bucket 11 as shown in Figure 9, the flexible connections 17 are lowered to permit the bottom closure doors 12 of the hoist bucket to open. When the cross bar 19 is raised as shown in Figure 8 to occupy a position adjacent the upper cross bar 15, the bottom closure doors of the hoist bucket 11 are closed.

The operating means for the elevator or hoist bucket including the cable 20 that is anchored at one end as at 21 to the upper cross beam 9 as shown in Figure 1, the cable travelling in a downward direction from its anchored end 21 through an opening 22 in the cross bar 15 to enclose the pulley 23 journaled in an opening formed in the vertically shiftable cross bar 19 and then upwardly and over the pulleys 24 and 25 at the upper end of the shaft 1. The cable 20 extends downwardly from the pulley 25 at the outer side of the shaft 1 and passes around the pulley 26 that is fixed to the shaft 27 with the end thereof secured to the drum 28 of the sta-

tionary engine 3. It will therefore be seen that when the cable 20 is wound on the drum 28, the cross bar 19 will be moved upwardly in a direction toward the cross bar 9 of the elevator to close the bottom doors 12 of the hoist bucket. Devices are provided and are adapted to be moved into the path of depending movement of the hoist bucket for arresting such movement whereby the weight of the contents of the hoist bucket will automatically open the bottom doors 12 and lower the cross bar 19 away from the cross bar 15, the separation of the cross bars rendering safety lock devices operative for the elevator to prevent accidental descent of the elevator during a dumping operation.

The locking devices for holding the elevator or hoist bucket against movement during a dumping operation are shown more clearly in Figures 8 to 10 and comprise a locking device at each end of the cross bar 15 that is engageable with the adjacent side guide rails 10. A bracket 29 projecting upwardly from each end of the cross bar 15 pivotally supports a lever 30, one end of which is bifurcated and toothed as at 31 for gripping the adjacent side guide rail 10, while the other end thereof has a link connection 32 with the lever 33 that is pivotally mounted in a slot in the cross bar 15 with one end of the lever 33 normally projecting beneath the cross bar 15 under the influence of the spring devices 34 interposed between the cross bar 15 and the inner ends of the lever 30. When the cross bar 19 is in its raised position as shown in Figure 8, the same engages the levers 33 to move the levers 30 upon their pivotal mounting for disengaging the toothed end 31 from the side guide rails 10. When the cross bar 19 is lowered as shown in Figure 9, the spring devices 34 exert a force on the inner end of the levers 30 to lower the toothed end 31 of the levers 30 and move them into engagement with the side guide rails 10. In this manner, the elevator or hoist bucket is locked in the shaft 1 against movement during its dumping operation. When the cross bar 19 is raised by the cable 20 to a position adjacent the cross bar 15, the levers 33 are operated for moving the levers 30 against the tension of the spring devices 34, this movement of the levers 30 disengages the toothed ends 31 of the side guide rails 10. Upward movement of the cross bar 19 causes the flexible connections 17 between said cross bar and the bottom closure doors to move the doors 12 upwardly to closed position, a further pull on the cable 20 moving the U-shaped frame comprising cross bar 15 and the hoist bucket in an upward direction.

In addition to the locking devices for the elevator or hoist bucket that are carried by the cross bar 15 of the inverted U-shaped frame that carries the elevator, there is pro-

vided a pair of adjustably mounted supporting bars with which the hoist bucket is engageable. The two supporting bars are shown more clearly in Figures 3, 6, 7 and 10, each supporting bar 35 being eccentrically pivotally supported at opposite ends as at 36 upon horizontally aligned cross bars 8. Corresponding sides of the supporting bars 35 are longitudinally rabbeted to form ledges 37 that are adapted to be positioned to receive and support side blocks 38 carried by the hoisting bucket 11.

The supporting bars 35 normally occupy positions illustrated in Figure 6 that are disposed outwardly of the path of movement of the elevator or hoist bucket and said supporting bars are adapted to be moved upon end bearings 36 to dispose the ledges 37 in the depending path of movement of the side blocks 38 upon the hoist bucket. The mechanism for moving the supporting bars 35 is shown more clearly in Figures 2, 3 and 10 and comprises a vertically shiftable rod 39 movable through openings formed in cross bars 8 at one side of the shaft structure 1, the upper end of the rod 39 being longitudinally slotted as at 40 for the reception of the pin 41 that pivotally connects adjacent ends of the links 42 that have their upper ends pivotally connected as at 43 to the supporting bars 35.

The vertically shiftable rod 39 is operatively engaged with a pair of trap doors 44 that are pivotally mounted at their outer edges as at 45 upon cross bars 8 adjacent the ground platform 6 to be operated for opening the doors to permit descending movement of the hoist bucket to a point below the ground line and further operating to close the trap doors during a dumping operation of the hoist bucket. The lower end of the rod 39 has the adjacent ends of a pair of links 46 pivotally connected thereto as at 47 while the other ends of the links are attached as at 48 to the trap doors 44 adjacent their swinging edges. Counter-balance weights 49 are associated with the trap doors 44 to aid the operating rod 39 in opening the doors.

The mechanism for operating the rod 39 comprises devices associated with the chute 4 and said devices are operated by the elevator or hoist bucket. The chute 4 comprises a bottom wall 50 and side walls 51, the forward edge of the bottom wall 50 of the chute being hingedly mounted as at 52 upon a cross bar 8. The support for the other end of the chute includes link and lever devices connecting the same to a shaft 54 clearly supported outwardly of the elevator shaft 1. As shown in Figures 2, 3, a pair of blocks 53 are carried by the shaft 1 on the corner posts 7 thereof above the hinged mounting 52 for the chute and rotatably supports a shaft 54. A bell crank

lever is fixed to one end of the shaft 54 and has one leg 55 thereof directed toward the chute 4 and connected thereto by the link 56 that is pivoted to the adjacent side wall 51 of the casing. An arm 55^a fixed at one of its ends to the other end of the shaft 54 has a link connection 56^a with the other side wall of the chute. When the shaft is rotated, the chute is caused to swing upon its hinged mounting 52 to be disposed either outwardly of the runway of the elevator shaft 1 or within the runway, and when disposed within the runway, the transverse bar 57 carried by the bottom 50 of the chute has the projecting ends thereof moved into engagement with the side guide rails 10 to support the chute in discharging position as shown in Figure 7. The outer end of the shaft 54 adjacent the arm 55^a has another arm 58 fixed thereto with the projecting end thereof pivotally connected to one end of a rack bar 59, the rack bar being normally influenced downwardly by the spring 60 into engagement with the toothed wheel 61 that in turn meshes with the rack bar 62 carried by the operating rod 39, this mechanism comprising the operating means for the rod 39, previously referred to. The other leg 63 of the bell crank lever that is fixed upon the shaft 54 has a link rod connection 64 with the lever 65 that is pivotally mounted as at 66 upon the adjacent side guide rails 10 at the upper end thereof in proximity of the cross beam 9, the lever 65 being moved upon its pivotal mounting 66 by a device carried by the hoist bucket for shifting the discharge chute and operating the rod 39 which in turn brings the supporting bar 35 in position to support the hoist bucket and operate the trap doors 44.

As shown in Figures 8 to 10, one side bar 14 of the inverted U-shaped frame that carries the elevator or hoist bucket has a rod 67 journaled in bearings 68 carried by the rod, the lower end of the shaft 67 carrying an offset arm 69 while the upper end of the rod 67 carries a cross head comprising side arms 70 and 71. One side wall 51 of the chute 4 has an arm 72 projecting upwardly therefrom with an inclined cam end 73 as shown in Figure 6 that is adapted to be engaged by the offset arm 69 of the rod 67 to effect rotation of the rod at the desired time for shifting the arms 70 and 71 comprising the head of the rod 67.

When the chute 4 is in the position shown in Figure 2, the trap doors 44 are in their open positions and the rod 39 retained in its upwardly shifted position by the counter-balance weights 49 as well as the rack and gearing connections between the rod 39 and the shaft 54 and when the hoist bucket is lowered by the cable 20 that is controlled by the stationary engine 3, said bucket passes downwardly through the shaft 1 to the de-

sired point below the ground level for charging. The hoist bucket after being charged is then raised in the shaft 1, the rod 67 having been shifted in a manner to be presently described for disposing the arm 70 of the cross head of said shaft in a position to engage the lever 65 at the side of its pivot adjacent the link rod 64. Continued upward movement of the hoist bucket will cause pivotal movement of the lever 65 and operation of the shaft 54 for moving the chute 4 upon its hinged mounting 52 to a position within the shaft 1 and to dispose the same beneath the hoist bucket as shown in Figure 7, the chute being supported in this position by the cross bar 57 upon the bottom thereof having its ends engaged with the side guide rails 10. During inward movement of the chute 4, the rack bar 59 operates the gear of the toothed wheel 61 which in turn engages the rack 62 for lowering the operating rod 39, the lowering movement of the operating rod 39 closing the trap doors 44 and also moving the supporting rods 35 upon their eccentric mountings 36 to dispose the ledges 37 thereof in position to receive the blocks 38 carried by opposite sides of the hoist bucket 11. The trap doors 44 being closed prevent the falling of material downwardly through the shaft to a pit beneath, while the supporting bars 35 prevent accidental falling of the hoist bucket. The stationary engine 3 is then reversed in its operation to permit lowering movement of the hoist bucket to dispose the side blocks 38 thereof upon the ledges 37 of the supporting bars 35. Slack in the cable 20 will permit the weight of the material in the hoist bucket to automatically open the bottom closure door 12 of the hoist bucket and in so doing, will lower the cross bar 19 away from the cross bar 15, which will permit the tensioned levers associated with the cross bar 15 to be operated and moved into clamping engagement with the side guide rails 10 for positively locking the hoist bucket against movement. When the hoist bucket is lowered into supporting engagement with the bars 35, the offset arms 69 upon the lower end 50 of the shaft 67 engages the cam end 73 of the arm 72 upon the chute 4 for shifting the shaft and also the cross head at the upper end thereof to dispose the arm 71 of the cross head in a position to engage the inner end of the lever 65 upon subsequent upward movement of the hoist bucket which will operate the arm lever 65 for moving the shaft 54 to displace the chute 4 laterally of the shaft, this movement also operating the rod 60 35 to elevate the same for opening the trap doors 44 and laterally displacing the supporting bars 35 out of the path of descending movement of the hoist bucket. During the downward movement of the hoist bucket, the arm 71 of the cross head of the shaft 67

engages the abutment 72 carried by a cross bar 8 for shifting the cross head and shaft 67 to dispose the arm 70 of the cross head in a position to engage the outer end of the lever 65 upon the following upward movement of the hoist bucket.

Devices are associated with the shaft 27 that carries a pulley 26 over which the hoisting cable 20 passes, for indicating the exact position of the hoist bucket in the shaft and are shown more clearly in Figures 4, 5 and 11. The shaft 27 has a belt and pulley connection 73^a with the worm shaft 74 of an indicator that comprises a dial 75 and an indicator finger 76, the dial having numbers 75 thereon indicative of differential elevations 80 in the shaft.

From the above detail description of the invention, it is believed that the construction and operation of the invention will be fully understood, and while there is herein shown and described the preferred embodiment of the invention, it is nevertheless to be understood that minor changes may be made therein without departing from the spirit 85 and scope of the invention as claimed.

What we claim as new is:—

1. In a shaft and elevator construction for handling material, a shaft, an elevator comprising a hoist bucket movable in the shaft, a pair of trap doors in the shaft, a chute hinged to the shaft, operative devices connecting the chute and trap doors, and cooperating devices carried by the chute and hoist bucket for operating the chute and trap doors for moving them into and out of operative positions.
2. In a shaft and elevator construction for handling material, a shaft, an elevator comprising a hoist bucket movable in the shaft, a pair of trap doors in the shaft, a chute hinged to the shaft, operative devices connecting the chute and trap doors, cooperating devices carried by the chute and hoist bucket for operating the chute and trap doors for moving them into and out of operative positions, and means operated by the chute and trap door connecting means to be moved into a position to receive and support the hoist bucket during a dumping operation.
3. In a shaft and elevator construction for handling material, a shaft, an elevator comprising a hoist bucket movable in the shaft, a pair of trap doors in the shaft, a chute hinged to the shaft, operative devices connecting the chute and trap doors, cooperating devices carried by the chute and hoist bucket for operating the chute and trap doors for moving them into and out of operative positions, and means for locking the hoist bucket against movement.
4. In a shaft and elevator construction for handling material, a shaft, an elevator comprising a hoist bucket movable in the shaft,

- a pair of trap doors in the shaft, a chute hinged to the shaft, operative devices connecting the chute and trap doors, and cooperating devices carried by the chute and 5 hoist bucket for operating the chute and trap doors for moving them into and out of operative positions, guide rail in the chute for the hoist bucket and the chute being moved into supporting engagement with 10 the rails when in discharging position.
5. In a shaft and elevator construction for handling material, a shaft, an elevator comprising a hoist bucket movable in the shaft, a chute hinged to the shaft and normally 15 occupying a position outwardly of the run-way, cooperating devices carried by the chute and hoist bucket for moving the chute into and out of operative position and co-operating devices carried by the bucket and 20 shaft rendered operative when the chute moves into the shaft for supporting the bucket while in dumping position.
6. In a shaft and elevator construction for handling material, a shaft, an elevator comprising a hoist bucket movable in the shaft, a chute hinged to the shaft and normally 25 occupying a position outwardly of the run-way, cooperating devices carried by the chute and hoist bucket for moving the chute into and out of operative position, said co-operating devices including a journalled 30 shaft having link and bar connections with the chute, a lever pivoted on the elevator shaft, connections between the journalled 35 shaft and lever, an arm on the hoist bucket to operate the lever for moving the chute and cooperating devices carried by the bucket and shaft rendered operative when the chute moves into the shaft for supporting 40 the bucket while in dumping position.
7. In a shaft and elevator construction for handling material, a shaft, an elevator comprising a hoist bucket movable in the shaft, a chute hinged to the shaft and normally 45 occupying a position outwardly of the run-way, cooperating devices carried by the chute and hoist bucket for moving the chute into and out of operative position, said co-operating devices including a journalled 50 shaft having link and bar connections with the chute, a lever pivoted on the elevator shaft, connections between the journalled 55 shaft and lever, and an arm on the hoist bucket to operate the lever for moving the chute, the arm on the hoist bucket being movable to engage opposite ends of the lever for moving the chute in opposite directions.
8. In a shaft and elevator construction for handling material, a shaft, an elevator comprising a hoist bucket movable in the shaft, a chute hinged to the shaft and normally 60 occupying a position outwardly of the run-way, cooperating devices carried by the chute and hoist bucket for moving the chute into and out of operative position, said co- 65 operating devices including a journalled shaft having link and bar connections with the chute, a lever pivoted on the elevator shaft, connections between the journalled 70 shaft and lever, an arm on the hoist bucket to operate the lever for moving the chute, the arm on the hoist bucket being movable to engage opposite ends of the lever for moving the chute in opposite directions, and means on the chute and elevator shaft to be 75 engaged by the arm for setting the arm in position to engage the proper end of the lever.
9. In a shaft and elevator construction for handling material, a shaft, an elevator comprising a hoist bucket movable in the shaft, a chute hinged to the shaft and normally 80 occupying a position outwardly of the run-way, cooperating devices carried by the chute and hoist bucket for moving the chute into and out of operative position, said co-operating devices including a journalled 85 shaft having link and bar connections with the chute, a lever pivoted on the elevator shaft, connections between the journalled 90 shaft and lever, an arm on the hoist bucket to operate the lever for moving the chute, a pair of trap doors for the elevator shaft when the hoist bucket is in dumping position, and operative connections between the 95 trap doors and journalled shaft.
10. In a shaft and elevator construction for handling material, a shaft, an elevator comprising a hoist bucket movable in the shaft, a chute hinged to the shaft and normally 100 occupying a position outwardly of the run-way, cooperating devices carried by the chute and hoist bucket for moving the chute into and out of operative position, said co-operating devices including a journalled 105 shaft having link and bar connections with the chute, a lever pivoted on the elevator shaft, connections between the journalled 110 shaft and lever, an arm on the hoist bucket to operate the lever for moving the chute, the arm on the hoist bucket being movable to engage opposite ends of the lever for moving the chute in opposite directions, a pair of trap doors for the elevator shaft when the hoist bucket is in dumping position, and 115 operative connections between the trap doors and journalled shaft.
11. In a shaft and elevator construction for handling material, a shaft, an elevator comprising a hoist bucket movable in the shaft, a chute hinged to the shaft and normally 120 occupying a position outwardly of the run-way, cooperating devices carried by the chute and hoist bucket for moving the chute into and out of operative position, said co-operating devices including a journalled 125 shaft having link and bar connections with the chute, a lever pivoted on the elevator shaft, connections between the journalled shaft and lever, an arm on the hoist bucket 130

to operate the lever for moving the chute, the arm on the hoist bucket being movable to engage opposite ends of the lever for moving the chute in opposite directions, means 5 on the chute and elevator shaft to be engaged by the arm for setting the arm in position to engage the proper end of the lever, a pair of trap doors for the elevator shaft when the hoist bucket is in dumping 10 position and operative connections between the trap doors and journaled shaft.

12. In a shaft and elevator construction for handling material, a shaft, an elevator comprising a hoist bucket movable in the 15 shaft, a chute hinged to the shaft and normally occupying a position outwardly of the run-way, cooperating devices carried by the chute and hoist bucket for moving the chute into and out of operative position, said co- 20 operating devices including a journaled shaft having link and bar connections with the chute, a lever pivoted on the elevator shaft, connections between the journaled shaft and lever, an arm on the hoist bucket 25 to operate the lever for moving the chute, the arm on the hoist bucket being movable to engage opposite ends of the lever for moving the chute in opposite directions, a pair of trap doors for the elevator shaft when the 30 hoist bucket is in dumping position, operative connections between the trap doors and journaled shaft, including a vertically shift- 35 able rod, link connections between the lower end of the rod and trap doors, and rack and gear connections between the upper end of the rod and the journaled shaft.

13. In a shaft and elevator construction for handling material, a shaft, an elevator comprising a hoist bucket movable in the 40 shaft, a chute hinged to the shaft and normally occupying a position outwardly of the run-way, cooperating devices carried by the chute and hoist bucket for moving the chute into and out of operative position, said co- 45 operating devices including a journaled shaft having link and bar connections with the chute, a lever pivoted on the elevator shaft, connections between the journaled shaft and lever, an arm on the hoist bucket 50 to operate the lever for moving the chute, the arm on the hoist bucket being movable to en- 55 gage opposite ends of the lever for moving the chute in opposite directions, means on the chute and elevator shaft to be engaged by the arm for setting the arm in position to 60 engage the proper end of the lever, a pair of trap doors for the elevator shaft when the hoist bucket is in dumping position and operative connections between the trap doors 65 and journaled shaft, including a vertically shiftable rod, link connections between the lower end of the rod and trap doors, and rack and gear connections between the upper end of the rod and the journaled shaft.

14. In a shaft and elevator construction

for handling material, a shaft, an elevator comprising a hoist bucket movable in the shaft, a pair of trap doors in the shaft, a chute hinged to the shaft, operative devices connecting the chute and trap doors, coop- 70 erating devices carried by the chute and hoist bucket for operating the chute and trap doors for moving them into and out of operative positions, said hoist bucket comprising a body and an inverted U-shaped frame 75 carried thereby, a cross bar slidable in the side bars of the frame, a hoist cable for the bucket associated with the slideable cross bar and normally positioning the cross bar adjacent the upper end of the frame, guide 80 rails for the hoist bucket, and tensioned locking devices for the hoist bucket carried thereby and adapted to be engaged with the guide rails when the cross bar is lowered and the hoist bucket is in dumping position. 85

15. In a shaft and elevator construction for handling material, a shaft, an elevator comprising a hoist bucket movable in the shaft, a pair of trap doors in the shaft, a chute hinged to the shaft, operative devices 90 connecting the chute and trap doors, coop- erating devices carried by the chute and hoist bucket for operating the chute and trap doors for moving them into and out of operative position, means operated by the chute 95 and trap door connecting means to be moved into a position to receive and support the hoist bucket during a dumping operation, said hoist bucket comprising a body and an inverted U-shaped frame carried thereby, a 100 cross bar slidable in the side bars of the frame, a hoist cable for the bucket associated with the slideable cross bar and normally positioning the cross bar adjacent the upper end of the frame, guide rails for the hoist bucket, and tensioned locking devices for the hoist bucket carried thereby and adapted to be engaged with the guide rails when the cross bar is lowered and the hoist bucket is 105 in dumping position. 110

16. In a shaft and elevator construction for handling material, a shaft, an elevator comprising a hoist bucket movable in the shaft, a pair of trap doors in the shaft, a chute hinged to the shaft, operative devices 115 connecting the chute and trap doors, coop- erating devices carried by the chute and hoist bucket for operating the chute and trap doors for moving them into and out of operative positions, said hoist bucket comprising a body and an inverted U-shaped frame carried thereby, a cross bar slidable in the side bars of the frame, a hoist cable for the bucket associated with the slideable cross bar and normally positioning the cross bar ad- 120 jacent the upper end of the frame, hinged bottom doors for the hoist bucket having flexible connections with the slideable cross bar and closed when the cross bar is at its limit of upward movement engaged with the 125 130

head of the frame and opened when the cross bar is lowered and the hoist bucket is in dumping position, and means for holding the hoist bucket against movement rendered operative during dumping operation of the hoist bucket.

17. In a shaft and elevator construction for handling material, a shaft, an elevator comprising a hoist bucket movable in the shaft, a pair of trap doors in the shaft, a chute hinged to the shaft, operating devices connecting the chute and trap doors, cooperating devices carried by the chute and hoist bucket for operating the chute and trap doors for moving them into and out of operative position, means operated by the chute and trap door connecting means to be moved into a position to receive and support the hoist bucket during a dumping operation, said hoist bucket comprising a body and an inverted U-shaped frame carried thereby, a cross bar slidable in the side bars of the frame, a hoist cable for the bucket associated with the slidable cross bar and normally positioning the cross bar adjacent the upper end of the frame, hinged bottom doors for the hoist bucket having flexible connections with

the slidable cross bar and closed when the cross bar is at its limit of upward movement engaged with the head of the frame and opened when the cross bar is lowered and the hoist bucket is in dumping position, and means for holding the hoist bucket against movement rendered operative during dumping operation of the hoist bucket. 35

18. In a shaft and elevator construction for handling material, a shaft, an elevator comprising a hoist bucket movable in the shaft, a chute hinged to the shaft, operating devices for the chute comprising a lever pivoted on the shaft and an arm on the hoist bucket to engage and operate the lever for moving the chute into and out of operative positions, the arm being pivotally mounted on the hoist bucket, and means on the shaft and chute to engage and move the arm on its pivot to cause engagement of the arm with the desired end of the lever for the proper movement of the chute. 40

In testimony whereof we affix our signatures. 45
